UNITED STATES PATENT OFFICE.

NAPOLEON DU BRUL, OF CINCINNATI, OHIO.

DESIGN FOR A HAND-LEVER.

SPECIFICATION forming part of Design No. 23,680, dated October 2, 1894.

Application filed September 1, 1894. Serial No. 521,967. Term of patent 14 years.

To all whom it may concern.

Be it known that I, NAPOLEON DU BRUL, a citizen of the United States, and a resident of Cincinnati, in the county of Hamilton and 5 State of Ohio, have invented and produced a new and original Design for a Hand-Lever, of which the following is a specification, reference being had to the accompanying drawing, which is a perspective view showing my 10 design.

The leading features of my design consist in a cross-bar having a right angled projection at each end providing shoulders and extensions of the cross-bar, and a central stem 15 extending upwardly from the cross-bar, surmounted by a cross-bar having upwardly projecting arms at each end surmounted by forwardly and upwardly projecting arms terminating at one side in a head, and at the other 20 side in a head having an ear-shaped handle extending from above to a point beneath the head.

1 is a central stem having at its lower end a cross-bar 2 having right angled projections 3, providing shoulders 4, and extensions 5 of the cross-bar. Surmounting the central stem is another cross-bar 6 curved upward at the ends to provide arms 7, having forwardly projecting arms 8, and upwardly projecting arms 9 terminating at one side in a head 10, 25 and at the other side in a head 10^a having an ear-shaped handle 11 extending from a point above the head to the arm 9 beneath the head.

Having thus described my invention, the following is what I claim as new therein and 30 desire to secure by Design Letters Patent:

The design for a hand-lever; substantially as herein shown and described.

NAPOLEON DU BRUL.
